UNITED STATES PATENT OFFICE.

ANSON G. BETTS, OF TROY, NEW YORK.

ELECTROLYTIC APPARATUS.

No. 850,127.

Specification of Letters Patent.

Patented April 16, 1907.

Application filed May 11, 1904. Serial No. 207,367.

To all whom it may concern:

Be it known that I, ANSON G. BETTS, a citizen of the United States, residing at Troy, county of Rensselaer, and State of New York, have invented certain new and useful Improvements in Electrolytic Apparatus, of which the following is a specification.

The invention relates to such improvements, and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a top plan view of my improved electrolytic apparatus, partly broken away for convenience of illustration. Fig. 2 is a vertical longitudinal section of the same, taken on the broken line 2 2 in Fig. 1. Fig. 3 is a vertical cross-section of the same, taken through one of the cathode-compartments on the broken line 3 3 in Fig. 1. Fig. 4 is a similar view taken through one of the anode-compartments on the broken line 4 4 in Fig. 1. Fig. 5 is a view in elevation of the left-hand end of the apparatus as shown in Fig. 1. Fig. 6 is a vertical cross-section of an end cathode-compartment, taken on the broken line 6 6 in Fig. 1.

This invention relates to electrolytic apparatus adapted for various uses, the same being particularly adapted in certain of its features for use where it is desirable to keep the anolyte separate from the catholyte, and being particularly adapted for the electrolysis of ferrous-sulfate copper-sulfate solutions for the production of metallic copper and ferric-sulfate solutions, also for diminishing by mechanical means the corrosion of an insoluble anode during such electrolysis.

The object of the invention is to provide a cheap and durable electrolytic apparatus for the uses stated.

Referring to the drawings, wherein the invention is shown in its preferred form, 1 represents a tank or vat, preferably made of wood, provided with a continuous lead lining 2. The tank is divided into a series of compartments by means of transverse partitions 3, which extend part way across the interior of the tank. The partitions are separated one from another along their bottom edges by sills 4, resting on the bottom of the tank,

and along their vertical edges by uprights 5 of the same width as the sills 4 and seated in notches 6 in said sills. (See Figs. 3 and 4.) Each sill and the pair of uprights seated thereon constitute a spacing-frame adapted to separate from one another by a definite distance the two partitions on opposite sides thereof, and said partitions and spacing-frames alternately arranged extend from one end of the tank approximately to the other end thereof, sufficient space only being left for the insertion of a pair of wedges 7 between the assembled partitions, spacing-frames, and the end of the vat, as shown in Fig. 2. Said wedges are driven tightly into position to force the alternately-arranged partitions and spacing-frames into close engagement with each other, so as to provide water-tight joints therebetween. I prefer the use of the wedges to secure such tight joints; but the wedges may be omitted, provided the partitions and spacing-frames tightly engage one another in series.

The sills 4 may extend the whole width of the tank; but the partitions are preferably of less length than the interior width of the tank, and the uprights 5 are erected in line with the vertical edges of said partitions, thereby leaving a pair of longitudinal chambers 7 and 8, extending along the opposite sides of the tank from end to end thereof. The alternate compartments formed by said partitions and spacing-frames are in communication with the longitudinal chambers 7 and 8 by means of inlet-apertures 10, formed in the upper portion of the uprights adjacent to the chamber 7, and outlet-apertures 11, formed in the lower portion of the uprights adjacent to the other chamber 8. The other compartments are closed to both chambers 7 and 8. The compartments closed to the chambers 7 and 8 are adapted to contain the anolyte in contact with the anodes 12, while the other compartments, as well as the chambers 7 and 8, are adapted to contain the catholyte in contact with the cathodes 13, supported in said compartments, respectively.

The partitions separating the compartments are preferably made of some strong rigid material, such as wood, and are provided with numerous perforations 14, which are filled with wads of asbestos 17 or other material adapted to allow the ready passage of the electric current, but to offer great resistance to the passage of the electrolytes therethrough. The apertures in the parti-

tions are preferably formed as closely together as possible without destroying the rigidity of the partition. Other material, as rubber, lead, slate, glass, &c., may be used for the partitions, while charcoal, porous wood, or earthenware may be used for filling the perforations, it being desirable that the partitions should have sufficient rigidity and strength to form a support for the porous filling-pieces inserted in the partition-apertures and that the filling-pieces should be sufficiently porous to permit free passage of the electric current, while resisting the passage of the electrolytes therethrough. The compartments are preferably so arranged that the end compartments are cathode-compartments, formed in part by the lead-lined vat-walls or the wedges 6, as the lead lining of the vat is not attacked by the catholyte. The anolyte, however, which would have an injurious action upon the lead lining of the tank, is prevented from contact therewith by confinement in the anode-compartments, as above explained.

As a means for causing the circulation of the catholyte from the chamber 7 through the apertures 10 into the upper portions of various of the cathode-compartments, thence out through the apertures 11, from the lower ends of said compartments into the chamber 8, and thence back into the chamber 7, I place in one of the end cathode-compartments a diaphragm or partition 15, parallel with and a short distance from the spacing-upright at one end thereof, said partition extending above the level of the catholyte and to a point a short distance from the bottom of the compartment. The end upright adjacent to said partition is provided with an aperture 16, the lower edge of which is slightly above the general level of the catholyte, which aperture opens to chamber 7. A pipe 18, leading from a supply of air under pressure, is projected nearly to the bottom of the well formed between said end upright and said partition, as shown in Fig. 6, and the air escaping from the lower end of said pipe and rising through the catholyte in said well causes said catholyte within the well to rise to a level higher than the general level of the catholyte in the remainder of the vat and to overflow the bottom of the aperture 16, through which it passes into the neighboring chamber 7, tending to raise the level of the catholyte in said chamber. The catholyte thus caused to flow into the chamber 7 is taken from the chamber 8 through the bottom opening 11 in the adjacent upright at the end of the compartment having the well, through which compartment it passes beneath the inserted partition 15 into said well. The result of this operation is a constant tendency to raise the level of the catholyte in the chamber 7 and reduce its level in the chamber 8, causing a gravity flow of the catholyte

through the upper apertures 10 into the respective cathode-compartments and through the lower apertures 11 out of said compartments.

For the purpose of securing circulation of the anolyte I extend along the opposite sides of the vat a pair of troughs 19 and 20, supported upon horizontal cross-pieces 21, interposed between the vat-walls and the ends of the partitions and the spacing-uprights. The trough 19 is connected with the bottom of each anode-compartment by means of a siphon-tube 22, which extends up over the spacing-upright adjacent to said trough, and in like manner the trough 20 is connected with the upper end of each anode-compartment by a siphon-tube 23, which extends up over the neighboring spacing-upright. At one end of the vat is provided an exteriorly-located well 24, with the lower end of which the trough 19 is connected by means of a siphon-tube 25 and with the upper end of which the trough 20 is connected by means of a tube 26. A pipe 27, leading from a supply of air under pressure, is projected nearly to the bottom of said well, and the air thereby deposited near the bottom of said well rises in bubbles through the well-contained anolyte, raising the level of the same in the well above the general level of the anolyte and causing a flow through the tube 26 into the trough 20. This operation tends to continually lower the level of the anolyte in the trough 19 and to raise its level in the trough 20, causing a flow through the siphons 22 and 23 from the trough 20 into the upper ends of the respective anode-compartments and through the siphons 22 from the lower ends of said anode-compartments back into the trough 19.

The cathodes 13, which are in the form of plates, are suspended by means of hooks 30 from metallic cross-bars 31, which rest, respectively, at their outer ends upon the spacing-uprights at the respective outer ends of the cathode-compartments and at a point midway between the sides of the tank upon a contact-rod 32, which rests upon a bar 33, which extends longitudinally along the middle of the vat, resting upon the upper ends of the respective partitions. The contact-rod 32 is connected by wire 35 with the negative pole of an electrical generator. (Not shown.) The anodes are in the form of rods depending from metal cross-bars 36 of a carriage 37, mounted upon rollers 38, adapted to rest upon and travel longitudinally along the top surface of the side walls of the vat. The metal cross-bars from which the anode-rods depend are connected by a metal rod 39, which is connected by a wire 40 with the positive pole of said electrical generator.

To-and-fro movements can be imparted to the anode-carriage by means of the lever 41, connected at its upper end with said car-

riage by link 42, which lever is fulcrumed at 43 upon the end wall of the vat and is connected at its lower end with a rod 44, to which reciprocating movements are imparted by the crank 45, with which said rod is connected by a pitman 46. The crank 45 may be operated by power in any known manner, and the rod 44 may be extended to operate the anode-carriages of a number of tanks, if desired. During electrolysis to-and-fro movements are thus imparted to the anodes within their respective compartments, which movements I have discovered materially diminish polarization and increase the life of the anodes. A reciprocating motion of one-inch amplitude has been found to give good results.

Various materials may be used for the anodes and cathodes, such as lead and carbon for the anodes and lead, copper, and carbon for the cathodes. The troughs 19 and 20 may be made of lead, if desired, as they are easily accessible and can be quickly replaced when their usefulness has been impaired by the action of the anolyte.

For certain purposes of the above invention a suitable catholyte may consist of an aqueous solution containing about four per cent. of iron in the form of ferrous sulfate, two and one-half per cent. of copper in the form of copper sulfate, and two per cent. of free sulfuric acid; and a suitable anolyte may consist of an aqueous solution containing about three per cent. of iron in the form of ferric sulfate, one per cent. of iron in the form of ferrous sulfate, three-fourths per cent. of copper in the form of copper sulfate, and two per cent. of free sulfuric acid, the same being substantially free from halides. By the term "halide" I mean the simple combination of a halogen or cyanogen with an element, ammonium or equivalent.

My apparatus as above described is suitable for the electrolysis of solutions for other purposes than metal deposition and production of oxidizing solutions in the anolyte. For instance, oxidation and reduction of organic substances may be carried on in the anode and cathode compartments, respectively.

The level of the catholyte is indicated by the broken line 50 and the level of the anolyte by the broken line 51, as shown in Figs. 3 and 4.

I make no claim herein to the process or method above disclosed, the same forming the subject-matter of another application filed by me February 16, 1905, Serial No. 245,884.

What I claim as new, and desire to secure by Letters Patent, is—

1. In an electrolytic tank and in combination, a lining of lead, certain compartments in said tank containing an anolyte which contains dissolved a peroxidized compound of a metal, and certain other compartments in

the tank containing a catholyte substantially free from said compound; an intervening layer of catholyte between the anolyte and said lining; and anodes immersed in the anolyte and cathodes in the catholyte. 70

2. In an electrolytic apparatus, the combination with a vat or tank; an electrolyte containing an oxidizable ingredient; of insoluble anodes, and means for imparting to the anodes a reciprocating movement through the electrolyte. 75

3. In an electrolytic apparatus, and in combination, a vat or tank having compartments separated from one another by walls pervious to the electric current and substantially impervious to the electrolytes; in certain of said compartments insoluble anodes, and an anolyte containing peroxidized compound of a metal; in the other of said compartments, a catholyte containing a compound of the same metal in a lower state of oxidation, and cathodes on which metal is electrodeposited; and means for imparting to the anodes a movement through the anolyte. 80

4. In an electrolytic apparatus, and in combination, a vat or tank, having compartments separated from one another by walls pervious to the electric current and impervious to the electrolytes; in certain of said compartments insoluble anodes, and an anolyte containing ferric and ferrous sulfates; in the other of said compartments a catholyte containing ferrous and cupric sulfates, and cathodes on which copper is electrodeposited; and means for imparting to the anodes a movement through the anolyte. 90

5. In an electrolytic tank, and in combination, anode-compartments containing a liquid, in which is dissolved an oxidizable ingredient, and insoluble anodes immersed therein, and cathode-compartments separated from said anode-compartments by suitable electrolytic diaphragm, containing a solution in which is immersed a cathode; and means for imparting to the anodes motion through the anolyte. 105

6. In an electrolytic tank, and in combination; anode and cathode compartments therein, separated by suitable electrolytic diaphragms; troughs exterior to said compartments, and horizontally placed at an angle to said diaphragms, said troughs containing anolyte, and communicating with the anode-compartments by means of siphons; with means for causing a motion of anolyte from one of said troughs to the other. 115

7. In combination with an electrolytic tank, containing separate compartments for anolyte and catholyte, said compartments being separated by suitable electrolytic diaphragms, a movable frame above said tank, from which depend insoluble anodes, dipping into the anolyte, and means for imparting to said frame a reciprocating motion. 125

8. In combination with an electrolytic 130

tank, containing separate compartments for anolyte and catholyte, said compartments being separated by suitable electrolytic diaphragms, a movable frame above said tank, 5 from which depend carbon anodes, dipping into the anolyte, and means for imparting to said frame a reciprocating motion.

In testimony whereof I have hereunto set my hand this 14th day of April, 1904.

ANSON G. BETTS.
